UNITED STATES PATENT OFFICE.

MARCUS M. WHIPPLE, 2d, OF SHARON, MASSACHUSETTS.

DESIGN FOR A FEED-PLATE FOR LEATHER-SPLITTING MACHINES.

SPECIFICATION forming part of Design No. 29,477, dated October 11, 1898.

Application filed July 23, 1898. Serial No. 686,737. Term of patent 7 years.

To all whom it may concern:

Be it known that I, MARCUS M. WHIPPLE, 2d, of Sharon, in the county of Norfolk and State of Massachusetts, have invented and produced a new and original Design for a Feed-Plate for Leather-Splitting Machines, of which the following is a specification, reference being had to the accompanying drawing, forming part thereof.

10 The principal feature of my new design for a feed-plate of leather-splitting machines consists of the arrangement of the diverging guides thereon.

In the drawing the feed-plate 5 has the

beveled edge 6 and the depending member 7. 15 The ribs or guides 8 are arranged in parallel lines on the member 7, extending over the surface of the plate 5 in curves which diverge from the longitudinal central portion of the plate toward the ends thereof and tapering 20 to points toward the edge 6.

What I claim is—

The design for a feed-plate for leather-splitting machines as herein shown and described.

MARCUS M. WHIPPLE, 2d.
